BANK OF AMERICA, A CORPORATION OF CALIFORNIA

ARTICLE, METHOD, AND MACHINE FOR MANUFACTURE

Application filed December 5, 1931, Serial No. 579,183. Renewed June 12, 1933.

This invention relates to pads or other forms of articles impregnated uniformly with materials as an abrasive and to a machine and a method for producing these pads. Since the invention has been used successfully to produce pads useful for polishing silver and gold ware, I shall preferably describe the method, machine and article of my invention as related to the production of such pads. However, it is otherwise useful and the invention is of a generic nature.

In the polishing of precious and semi-precious metals, the use of abrasives is common to remove the thin, darkened exterior film and reveal the true nature of the metal in a polished and lustrous state. However, while this use of abrasives has been common, the disadvantage of having the abrasive cut and scratch the metal has also been encountered, as has the inconvenience of dirty hands from applying the abrasive to the metal. The present invention enables a polishing material to be supplied which obviates these disadvantages.

It is an object of the invention to provide an improved polishing pad enabling the surface of an article to be polished without danger of scratching or cutting the surface and without inconvenience to the person using the article.

Another object of the invention is to provide a method of manufacture for forming an article including a fibrous mass impregnated with a finely divided solid uniformly distributed.

Another object of the invention is to provide a method of manufacture for an article whereby the article, a mass of fibrous material, is impregnated with finely divided solid material without coalescence and forming of aggregates of said fine solids in said mass of fibrous material.

Another object of the invention is to provide a machine for producing the article of my invention; my machine enables material to be processed to produce the very desirable article.

A further object of the invention is to produce an abrasive article of a fibrous mass as cotton which is uniformly impregnated with a finely divided solid as jeweler's rouge.

The invention possesses other advantageous features and objects, some of which, with the foregoing will appear upon consideration of the following wherein I have dis-

closed, as required, only the preferred manner of practising my invention and employing my method, producing my article and constructing my machine.

In practising the preferred method of my invention, I have used a mass of fibrous material and have incorporated therein the desired material. Thus, in the preferred form of the invention, I impregnate or disperse jeweler's rouge throughout a mass of cotton fibers, preferably matted, short, staple cotton known as cotton linters. The cotton mass is loosened and the abrasive then beaten into the fibrous mass so that it is uniformly dispersed throughout the mass. Instead of cotton, other materials can be used as wool, mixtures of wool and cotton, and kapok. The material should be capable of forming interstices between its fibers so that the abrasive can work through the material and thereby impregnate the material. Fibrous material is preferred since the abrasive can be applied successfully to indentations in the articles to be polished.

In accordance with my invention, the fibrous mass and the abrasive are treated so that the abrasive, or other solid, does not coalesce, or collect, into small lumps which are large enough to scratch a precious metal surface. I have found that if the fibrous mass is first dried and, while dry, impregnated, a superior product from the standpoint of uniform particle size and consequent freedom from scratching, is secured.

I prefer that the mass of fibrous material be not only dry but hot. The abrasive is also hot and substantially moisture free, being predried by heating to above 100° C.—usually 200° C. Dispersion of the abrasive through the fibrous mass is thus facilitated since the mass, on drying, fluffs and expands, becoming soft and lending itself readily to dispersion of the abrasive and the abrasive dusts. The abrasive particles, if not heated and dried, cannot work through the interstices of the material as thoroughly as when the abrasive is dry. Because of its fine state of division, the material is hygroscopic in nature and coalesces into aggregates. When dry, the abrasive and the abrasive dusts enter the material readily.

To facilitate distribution of the abrasive through the fibrous mass and to secure uniform dispersion, I prefer that the fibrous mass be mechanically beaten, loosened and

separated and that an abrasive laden atmosphere be maintained in which the fibrous mass is beaten, loosened and separated. The abrasive then can penetrate and be uniformly distributed throughout the interstices in the cellulose mass. Working of the fibrous, cellulose mass by beating it so it fluffs out alternately in various directions enables a uniform form distribution of the abrasive to be secured.

After the fibrous mass has been worked and the abrasive incorporated, I prefer that the mass be compressed and reduced in size so that the mass becomes compact. Abrasive particles thus become relatively fixed in the mass.

In a preferred production, I have used cotton fibers and jeweler's rouge. However, other fibrous materials can be used as kapok, 20 wool in fibrous, non-woven form, and other abrasives as fine, iron free diatomaceous earth, tripoli and chalk.

Other advantages and features of my invention will appear upon consideration of the following explanation of the operation 25 of my machine as employed to produce a polishing material.

In the drawings, accompanying and forming a part of this specification, Figure 1A is 30 a right hand view of a portion of my machine.

Figure 1B is a complementary left hand view of the remainder of my machine. Figure 35 1A overlaps a portion of Figure 1B. The two figures taken together comprise a diagrammatic side view of my invention.

In this preferred embodiment I include a machine frame 6 of suitable structure elements to carry the units of the machine. 40 Feed rollers 7 support and feed material, to be formed into a pad, into oven 8 which includes electric heater 9. Heater 9 directs heat, including radiant heat, onto material drawn over support wires 11 and against baffle 12 carried on removable cover 13. Cover 13 includes vent 14 for the regulated escape of hot, moisture laden air.

Wires 11 extend beyond oven 8 to support 50 material to receive solid finely divided material from vibrating screen 16. Material is fed from hopper 17 by feed screws 18 onto screen 16. After receiving material passed by screen 16, the material is beaten by beaters 19. Screen 16 and beaters 19 are enclosed in a housing 21 having a collector and outlet 22. Beaters 19 are rapidly vibrated and beat the abrasive material laden fibrous mass vigorously to remove excess abrasive material and to incorporate the abrasive material uniformly throughout the base material.

Spring pressed rollers 23, enclosed in housing 25, press the fluffed and beaten material into a compact mass. Finished material is formed into a roll on collector rollers 24.

65 Power to drive collector rollers 24, spring

pressed rollers 23, screen 16, beaters 19 and rollers 7 is furnished by electric motor 26 connected to speed reducer 27. From speed reducer 27, power is furnished to rollers 24, spring pressed rollers 23 and feed rolls 7 by 70 sprockets 28 and chains 29. Beaters 19 are reciprocated by crank arm 31, between gears 32 connected to beaters 19, and crank 33. Screen 16 is vibrated by crank arm 34 between shaft 36, which is connected to spring 75 mounted screen 16, and crank 33. Feed screw 18 is rotated by rod 37 engaging eccentric 38. Rod 37 is connected to arm 39 which carries pawl 40 which is oscillated to rotate ratchet 41. Ratchet 41 is mounted on feed screw shaft 42 to rotate feed screw 18 to discharge material onto screen 16. The various units are moved in timed relationship to advance continuously material through the machine.

In operation, material is fed over a straight line path through the communicating oven 8 and housings 21 and 25. A roll of material as a sheet of loose, unwoven, matted cotton is placed on rolls 7. Oven 8 80 has previously been brought up to and maintained thermostatically at a suitable temperature, above 100° C., to drive off moisture, usually 220° C. Upon the material entering and passing through the oven 8, it 85 dries and becomes fluffy and soft, expanding as it does so. Screen 16 discharges a shower of screened and extremely, finely divided abrasive onto the fluffed material beneath it. Material remains in oven 8 for a 90 period long enough to dry the material without harming the material. This is usually about ten to thirty minutes, depending on the thickness of the material.

Because of the communication with oven 105 8 and proximity thereto, predried material discharged on screen 16 is maintained dry and free of moisture. Wires 11 are spaced apart and support the material during drying and application of abrasive. After application of abrasive, beaters 19 vigorously beat, fluff and impregnate the abrasive through the material. Since the material is dry this occurs readily. About five pounds of jeweler's rouge are applied to every fourteen pounds of material, about three and a half pounds of rouge being incorporated into the cotton.

Beaters 19 and screen 16 also maintain an atmosphere of dispersed abrasive in housing 120 21 which is constantly circulated into contact with the material so that the material finally is impregnated with abrasive. Material in excess falls into collector 22.

After being beaten, fluffed and thoroughly 125 impregnated with abrasive, the material is compressed by spring pressed rollers 23 which are urged together by springs 46. This packs the material into compact form. Thereafter the material is wound into roll 130

form on collector rollers 24 to be subsequently subdivided into any smaller size desired.

Oven 8 and housing 25 form seals at either end of housing 21 in which the abrasive laden atmosphere is maintained. This prevents direct escape of abrasive to the atmosphere.

I claim:

1. The method of forming an abrasive and 10 polishing pad and the like comprising riding a pad of fibrous material of moisture, discharging abrasive onto said pad, loosening said pad to incorporate said abrasive thoroughly throughout said pad and beating said 15 abrasive throughout said loosened pad of material, and thereafter compressing said loosened pad into original form.

2. The method of forming an abrasive pad 20 from a mass of fibrous material comprising heating said mass of material to remove moisture, loosening said mass of material, incorporating an abrasive into said mass while said mass is hot, beating said mass of material with said abrasive, and compressing 25 said mass of material into compact form.

3. The method of forming an abrasive pad 30 from a mass of fibrous material comprising heating said mass of material to remove moisture, incorporating an abrasive into said mass while said mass is hot, beating said mass of material with said abrasive, and compressing 35 said mass of material into compact form.

4. The method of forming an abrasive pad 40 from a mass of fibrous material comprising heating said mass of material to remove moisture, loosening said mass of material, incorporating an abrasive into said mass, and compressing said mass of material into compact form.

5. The method of forming an abrasive pad 45 from a mass of fibrous material comprising loosening said mass of material, incorporating an abrasive into said mass, beating said mass of material with said abrasive, and compressing said mass of material into compact form.

6. The method of forming an abrasive pad 50 from a mass of fibrous material comprising incorporating an abrasive into said mass, beating said mass of material with said abrasive, and compressing said mass of material into compact form.

7. The method of forming an abrasive pad 55 from a mass of fibrous material comprising heating said mass of material to remove moisture, incorporating an abrasive into said mass while said mass is hot, and beating said mass of material with said abrasive.

8. The method of forming an abrasive pad 60 of iron oxide and a mass of cotton fibers comprising heating said cotton fibers to remove

moisture therefrom, applying iron oxide particles to said mass of dried fibers, and beating said cotton fibers and iron oxide to incorporate said oxide throughout said mass of fibers and to loosen said mass of fibers. 70

9. The method of forming an abrasive pad of iron oxide and a mass of cotton fibers comprising heating said cotton fibers to remove moisture therefrom, applying iron oxide particles to said mass of dried fibers, beating 75 said cotton fibers and iron oxide to incorporate said oxide throughout said mass of fibers and to loosen said mass of fibers, and compressing said loosened mass of fibers.

10. A machine for producing abrasive pads and the like comprising feeding means for a length of a fibrous mass of material, means for drying said length of material during feeding thereof, means for applying abrasive to said length of material during feeding 80 thereof, and means for beating said abrasive into said material.

11. A machine for producing abrasive pads and the like comprising feeding means for a length of a fibrous mass of material, means for drying said length of material during feeding thereof, means for applying abrasive to said length of material during feeding thereof, means for beating said abrasive into said material, whereby said fibrous mass is 85 loosened, and means for compressing said loosened mass into compact form.

12. The method of forming an abrasive pad comprising heating a mass of base material to dry, loosen and fluff said material, 100 depositing an abrasive on said material, and beating said material to distribute said abrasive.

13. The method of forming an abrasive pad comprising heating a mass of base material to dry, loosen and fluff said material, depositing an abrasive on said material, beating said material to distribute said abrasive and compressing said fluffed and loosened material. 105

14. The method of forming an abrasive pad and the like comprising heating a mass of cotton linters to about 100° C. to remove moisture therefrom, incorporating in said hot, moisture free mass a dry, finely divided powdered material, and beating the mass to distribute the powdered material therethrough. 115

15. The method of forming a pad comprising heating a mass of base material to dry and fluff said material, depositing a finely divided powdered material on said dry material, and beating said base material to distribute said powdered material therethrough. 120
